UNITED STATES PATENT OFFICE.

AMES VAN WART, OF NEW YORK, N. Y.

DESIGN FOR AN ALTO-RELIEF.

Specification forming part of Design No. 5,057, dated June 27, 1871.

To all whom it may concern:

Be it known that I, AMES VAN WART, of the city, county, and State of New York, have invented a new and Improved Design for an Alto-Relief; and I do hereby declare that the following is a full, clear, and exact description thereof, which will enable others skilled in the art to make and use the same, reference being had to the accompanying photographs forming part of this specification.

The nature of my design, which is entitled

"Phæton driving the chariot of the sun," is fully represented in the accompanying photographs, to which reference is made.

I claim as my invention—

The design for an alto-relief, as shown.

The above specification of my invention signed by me this 5th day of June, 1871.

AMES VAN WART.
